FRITZ LUNDSTEN, OF CORONA, NEW YORK, ASSIGNOR OF ONE-HALF TO
THEODOR ESKILSSON, OF ASTORIA, NEW YORK.

SAFETY DEVICE FOR ELEVATORS.

No. 817,431.

Specification of Letters Patent.

Patented April 10, 1906.

Application filed November 16, 1905. Serial No. 287,554.

To all whom it may concern:

Be it known that I, FRITZ LUNDSTEN, a citizen of the United States, and a resident of Corona, county of Queens, and State of New York, have invented a certain new and useful Improvement in Safety Devices for Elevators, of which the following is a specification.

My invention relates to safety devices for elevators; and its object is to improve upon structures of this kind now in use and to provide a device for quickly and powerfully clamping an elevator-car to the guides over which it is adapted to run.

I will describe my invention in the following specification and point out the novel features thereof in claims.

Referring to the drawings, Figure 1 is a diagrammatic view, in side elevation, of an elevator-car and certain connected apparatus which may be used in carrying out my invention. Fig. 2 is a plan view, partly in section, of my safety device, showing sections of the guides which it is intended to clamp. Fig. 3 is a detail of certain of the parts shown in Fig. 2, but in different relative positions. Fig. 4 is a side elevation of a part of the apparatus shown in Fig. 2. Fig. 5 is a sectional end view of certain of the parts, the section being taken through the line A B of Fig. 4. Fig. 6 is a detail of a cam. Fig. 7 is a detail of a part of a tripping device which I use in carrying out my invention.

Like characters of reference designate corresponding parts in all of the figures.

10 designates an elevator-car to the bottom of which my device is attached.

11 is a hoisting-rope for the car.

12 is a governor-rope connected to run with the car. This governor-rope runs under a sheave 13, situated near one end of the car's travel. It may be weighted, as at 15, and pawls 16 16 may be provided, if desired, to engage with ratchets in the sides of the weight 15 to prevent its upward movement.

The governor-rope 12 runs over another sheave 14 near the other end of the car's travel, which is connected to a governor or speed-regulator 17 by suitable gearing 18.

50 The speed-governor is arranged to actuate a gripping device 19, which grips and positively locks the governor-rope whenever the car runs in excess of normal speed. It may be regulated or set to operate at any desired

speed and may be arranged to operate when 55 the car is running in either direction. The governor-rope is yieldingly connected to the car at 12' and is so arranged that when the governor-rope 12 is stopped and the car continues to move it will pull away from 60 the yieldingly connection. This will cause the rope 12^a, which is attached to governor-rope 12, to be pulled through the pulleys 12^b 12^b and to be unwound from a drum 31 on the safety device, and thereby impart a rotary 65 motion to the winding-drum 31. It is sometimes desirable to rotate the winding-drum 31 by hand from the car, and for this purpose I have provided another rope 12^c on the winding-drum and attached this rope to a 70 handle 12^d within reach of the operator in the car.

I will now refer to Fig. 2 and describe the clamping device or safety device for the elevator-car, which is there illustrated. The 75 winding-drum 31 is rotatably supported by brackets 34 34, which are rigidly mounted upon a frame 30 30, which holds the safety device and which is preferably attached to the bottom of an elevator-car. The drum 80 31 may be grooved, as shown at 32, for the reception of the rope 12^a, which is attached to it. The inside of the drum is provided with right and left hand screw-threads, in which screws 35 and 36 work. The outer 85 end of these screws are attached to wedge-shaped cams 25 25. 21 21 designate gripping-jaws, which are eccentrically pivoted at 40 to the frame 30 in a manner which will be specifically pointed out later, as it forms 90 an important part of my invention. These jaws are adapted to be moved against and to clamp guides 22 22, over which the car 10 is arranged to run, and to thereby lock the car to the guides. The inner ends of jaws 21 21 95 may be provided with antifriction-rollers 24 24, which are arranged to coact with the wedge-shaped cams 25, as will be fully described hereinafter. 60 is a locking-lever which is pivoted at 61 to a bracket 64, which 100 is attached to the frame 30. One end 62 of this locking-lever is held against a cam 70, which is attached to or else is an integral part of the drum 31, by a spring 65. A slotted guide 66 may be provided to prevent a 105 side movement of lever 60. The other end 63 of this locking-lever rests upon a projecting lug 45. The gripping-jaws 21 are

pivoted at 40 as follows: A pin 41 is loosely mounted in frame 30. A circular hub 42 is eccentrically attached to this pin. The jaw 21 is provided with a circular hole which fits over this hub. A short arm 44 is rigidly attached to the outer end of pin 41, and the projecting lug 45, upon which the end 63 of locking-lever 60 rests, is at the end of this short arm. A spring 43 is provided for the purpose of turning pin 41 and its attached parts around, when released, into the position shown in Fig. 3. The parts above described are the same for all of the pivoted joints of the jaws 21, except that the short arm 46 of one of each pair of pivots need not have any projecting lug, such as 45, upon it. The cam 70, which is on drum 31 and upon which one end of lever 60 rests, may be of the form shown in Fig. 6. The greater part of its surface is concentric with the center line of the screws 35 and 36. One or more depressions 72 may be provided on its surface.

I will now describe the operation of this invention. Under usual conditions, when the car is running, the various parts will be in the positions in which they are shown in Fig. 2. It may be seen from this figure that the parts of the gripping-jaws 21 21 which are near the guides 22 22 are so placed that there is a considerable clearance between the jaws and the guides. This is a valuable feature, for it prevents all friction between these parts while the car is running, and consequently there is no wear on these parts.

Whenever the car attains undue speed, so that the governor 17 acts and causes the rope 12^a to be pulled in the manner previously described, the winding-drum 31 and the cams 70 will be turned thereby. The first effect of this movement will be to depress the end 62 of locking-lever 60 and a similar lever 60^a, if more than one is provided, as is shown in Fig. 2, by the concentric part 71 of cam 70 being turned under the end of this lever. This will raise the opposite end 63 of locking-lever 60 until it is clear of the projecting lug 45 on the end of the short arm 44. It may be seen in Fig. 2 that this short arm 44 holds the short arm 46 from turning. When the locking-lever releases these two arms 44 and 46, as just described, the springs 43 43 will cause them and the pins 41 41, to which they are attached, to be quickly rotated until they reach the positions against stops 47 and 48 indicated at 44' and 46' in Fig. 2 by dotted lines. When the eccentric hubs are in this position, they will not be returned to their former position by any pressure which may be brought upon them by the further operation of this device, because their position is such that the pressure of the jaws 21 upon them cannot force them back. The effect of this movement will be to quickly move the ends of the gripping-jaws 21 up to the guides 22; but it is not necessary that this movement

should bring the jaws into contact with the guides. The further movement of the winding-drum 31 will cause the right and left hand screws 35 and 36 to be moved toward each other and to thereby draw the wedge-shaped cams 25 25 together. These wedge-shaped cams will thus be drawn in between the anti-friction-rollers 24 24 and will cause the jaws 21 21 to grip the guides 22 22 with great force. This will lock the car 10 to the guides 22 22 and will thus bring it to rest, which of course will cause the movement of the winding-drum to cease. The various parts may be reset by hand. If desired, springs 26 26 may be provided to keep the jaws away from the guides when not forced on by the above-described mechanism.

Means may be provided for operating this device from the car independently of any action of the governor 17. For this purpose rope 12^c may be attached to winding-drum 31 and led up through the car, as shown in Fig. 1, with a handle 12^b attached to its end. It is obvious that if an operator in the car pulls up on this handle 12^b the operation of the device will be similar to that already described.

This arrangement, which I have now described, provides an ideal safety-stop for elevators, as the parts when not in use are free from wear and as its action is quick but is positive and powerful.

What I claim is—

1. In a safety device for elevators, the combination of a car, guides for the car, gripping-jaws upon the car, supports for said jaws and means for shifting the position of said supports.

2. In a safety device for elevators, the combination of a car, guides for the car, gripping-jaws upon the car, pivots for said jaws, means for shifting the position of the pivots and the jaws and additional means for moving the jaws.

3. In a safety device for elevators, the combination of a car, guides for the car, gripping-jaws upon the car, pivots for the jaws, means for shifting the position of said pivots toward the guides, and additional means for tightening the jaws upon the guides.

4. In a safety device for elevators, the combination of a car, guides for the car, gripping-jaws upon the car, pivots for the jaws, means for shifting the position of the pivots toward the guides quickly and additional means for tightening the jaws upon the guides more slowly with greater force.

5. In a safety device for elevators, the combination of a car, guides for the car, gripping-jaws upon the car, pivots for the jaws, spring-actuated means for shifting the position of the pivots toward the guides quickly and a screw for tightening the jaws upon the guides more slowly with greater force.

6. In a safety device for elevators, the com-

bination of a car, guides for the car, gripping-jaws upon the car, pivots for the guides, spring-actuated means for quickly shifting the position of the pivots toward the guides, 5 a locking device for said spring-actuated mechanism and a screw mechanism arranged to tighten the jaws upon the guides.

7. In a safety device for elevators, the combination of a car, guides for the car, gripping-jaws upon the car, eccentric pivots for the 10 jaws, spring-actuated mechanism for turning said eccentric pivots, a locking device for said spring-actuated mechanism, a cam for releasing said locking device and a screw 15 mechanism arranged to tighten the jaws upon the guides.

8. In a safety device for elevators, the combination of a car, guides for the car, gripping-jaws upon the car, eccentric pivots for the 20 jaws, spring-actuated mechanism for turning said eccentric pivots, a locking device for said spring-actuated mechanism, a cam for releasing said locking device, a screw mechanism arranged to tighten the jaws upon the 25 guides and means for actuating the cam and the screw by the motion of the car.

9. In a safety device for elevators, the combination of a car, guides for the car, gripping-jaws upon the car, eccentric pivots for the 30 jaws, spring-actuated mechanism for turning said eccentric pivots, a locking device for said spring-actuated mechanism, a cam for releasing said locking device, a screw mechanism arranged to tighten the jaws upon the 35 guides, means for actuating the cam and the screw by the motion of the car when the speed of the car has reached a predetermined limit.

10. In a safety device for elevators, the 40 combination of a car, guides for the car, gripping-jaws upon the car, eccentric pivots for the jaws, spring-actuated mechanism for turning said eccentric pivots, a locking device for said spring-actuated mechanism, a 45 cam for releasing said locking device, a screw mechanism arranged to tighten the jaws upon the guides, means for actuating the cam and the screw by the motion of the car when the speed of the car has reached a predetermined 50 limit, and means for actuating the cam and the screw by hand.

11. In a safety device for elevators, the combination of a car, guides for the car, gripping-jaws upon the car, eccentric pivots for the 55 jaws, spring-actuated mechanism for turning said eccentric pivots, a locking device for said spring-actuated mechanism, a cam for releasing said locking device, a screw mechanism arranged to tighten the jaws upon the 60 guides and a governor connected to run with the car and arranged to actuate the cam and the screw when the car has reached a predetermined limit.

12. In a safety device for elevators, the 65 combination of a car, guides for the car, grip-

ping-jaws upon the car, pivots for the jaws, mechanism to shift the position of the pivots toward the guides, a normally compressed spring arranged to actuate said mechanism, and a screw for tightening the jaws upon the 70 guides.

13. In a safety device for elevators, the combination of a car, guides for the car, gripping-jaws upon the car, pivots for the jaws, mechanism to shift the position of the pivots 75 toward the guides, a normally compressed spring arranged to actuate said mechanism, means for releasing said springs and a screw for tightening the jaws upon the guides.

14. In a safety device for elevators, the combination of a car, guides for the car, gripping-jaws upon the car, eccentric pivots for the jaws, means for turning said eccentric pivots, a spring arranged to actuate said pivot-turning means and to thereby move 85 the jaws toward the guides and to positively hold them in their moved position and further means for positively tightening the jaws upon the guides.

15. In a safety device for elevators, the 90 combination of a car, guides for the car, gripping-jaws upon the car, pivots for the jaws, spring-actuated means for shifting the position of the pivots toward the guides quickly and right and left hand screws for tightening 95 the jaws upon the guides more slowly with greater force.

16. In a safety device for elevators, the combination of a car, guides for the car, gripping-jaws upon the car, eccentric pivots for the 100 jaws, spring-actuated mechanism for turning said eccentric pivots, a locking device for said spring-actuated mechanism, a cam for releasing said locking device and right and left hand screws arranged to tighten the 105 jaws upon the guides.

17. In a safety device for elevators, the combination of a car, guides for the car, gripping-jaws upon the car, eccentric pivots for the jaws, spring-actuated mechanism for 110 turning said eccentric pivots, a locking device for said spring-actuated mechanism, a cam for releasing said locking device, right and left hand screws arranged to tighten the jaws upon the guides and means for actuating the 115 cam and the screws by the motion of the car.

18. In a safety device for elevators, the combination of a car, guides for the car, gripping-jaws upon the car, eccentric pivots for the 120 jaws, spring-actuated mechanism for turning said eccentric pivots, a locking device, for said spring-actuated mechanism, a cam for releasing said locking device, right and left hand screws arranged to tighten the 125 jaws upon the guides, means for actuating the cam and the screws by the motion of the car when the speed of the car has reached a predetermined limit.

19. In a safety device for elevators, the combination of a car, guides for the car, grip- 130

ping-jaws upon the car, eccentric pivots for the jaws, spring-actuated mechanism, for turning said eccentric pivots, a locking device for said spring-actuated mechanism, a 5 cam for releasing said locking device, right and left hand screws arranged to tighten the jaws upon the guides and a governor connected to run with the car and arranged to actuate the cam and the screws when the car has 10 reached a predetermined limit.

20. In a safety device for elevators, the combination of a car, guides for the car, gripping-jaws upon the car, eccentric pivots for the jaws, spring-actuated mechanism for 15 turning said eccentric pivots, a locking device

for said spring-actuated mechanism, a cam for releasing said locking device, right and left hand screws arranged to tighten the jaws upon the guides, a governor connected to run with the car and arranged to actuate the cam 20 and the screws when the car has reached a predetermined limit, and means for actuating the cam and the screws by hand.

In testimony whereof I have signed my name to this specification in the presence of 25 two subscribing witnesses.

FRITZ LUNDSTEN.
